UNITED STATES PATENT OFFICE

142,306

DESIGN FOR A STORE SERVICE TRUCK

Adrian J. Smith and William I. Evans,
Los Angeles, Calif.

Application January 17, 1945, Serial No. 117,484

Term of patent 14 years

(Cl. D14—3)

To all whom it may concern:

Be it known that we, Adrian J. Smith, a citizen of the United States, residing in the city of Los Angeles, in the county of Los Angeles, and State of California, and William I. Evans, a citizen of the United States, residing in the city of Los Angeles, in the county of Los Angeles and State of California, have invented a new, original, and ornamental Design for a Store Service Truck, of which the following is a specification, reference being had to the accompanying drawing, forming a part thereof, in which the single figure is a perspective view of a store service truck showing our new design.

We claim:

The ornamental design for a store service truck, as shown.

ADRIAN J. SMITH.
WILLIAM I. EVANS.
